FIG. 5.

INVENTOR:

Benjamin F. Hutches, Jr.
By Casper L. Redfield

ATTORNEY.

UNITED STATES PATENT OFFICE.

BENJAMIN F. HUTCHES, JR., OF ALLENDALE, NEW JERSEY.

STYLUS-PICKER.

1,368,728.

Specification of Letters Patent. Patented Feb. 15, 1921.

Application filed October 6, 1919. Serial No. 328,947.

To all whom it may concern:

Be it known that I, BENJAMIN F. HUTCHES, Junior, a citizen of the United States of America, and a resident of Allendale, county 5 of Bergen, and State of New Jersey, have invented certain new and useful Improvements in Stylus-Pickers, of which the following is a specification.

My invention is a stylus picker, and has 10 for its object the production of a simple and cheap device for picking up a single stylus from a receptacle in which a number are contained. While the present device may be used in a variety of positions or conditions, 15 it has special reference to the stylus used on phonograph records.

In the accompanying drawings—

Figure 1 is a plan;

Fig. 2 is a side elevation;

20 Fig. 3 is an enlarged elevation, partly in section, of a part of the device; and

Figs. 4 and 5 are plan and elevation, respectively, of a modification.

In the said drawings, 10 is a bracket which 25 is secured to a support 11 by the screw 12. Pivoted at 13 on the bracket 10 is an L-shaped arm 14 of hardened and magnetized steel.

The short arm 15 of the L has its extreme end 16 made of a smaller diameter 30 than the rest and over this is a cover 17 of copper, hard rubber, or other non-magnetic material. Only a small point of the magnetized end extends beyond the cover or 35 sheath 17.

The bracket 10 is secured adjacent to a receptacle 18 shown in dotted lines. This receptacle is for holding a supply of styli, and the L-shaped arm normally rests with 40 its magnetized end 16 upon the styli in the receptacle. The pivot at 13 is made loose so that the arm will fall to this position by gravity.

On the arm I provide a short projection 45 19 to which a person may apply his finger to lift the arm from the full line to the dotted line position. When so lifted, one of the styli in the receptacle will adhere to the magnetized end 16 as is shown in dotted lines at 20. But not more than one can adhere at a time because the exposed magnetized surface is great enough to permit of contact with only one at a time.

It will be evident that if a supply of styli

be placed in the receptacle 18, and the arm 55 left to fall so that the magnetized end 16 rests upon them, then, if the arm be raised, one stylus will be separated from the mass and elevated to a position where it may be grasped conveniently by the fingers. If 60 the arm is released by simply letting go of it, it falls again to contact with the mass of styli. When again raised, another stylus will be separated from the mass and elevated. And so on as long as any stylus 65 remain in the receptacle.

In the form shown in Figs. 4 and 5, I provide an extension 21 to the bracket 10, which extension projects under the arm 14 and has an opening 22 through which the 70 arm 15 passes. In this case the arm 15 is only a trifle larger in diameter than is the diameter of the styli to be lifted, and the hole 22 is of a size too small to permit two styli to pass through at the same time. 75 Otherwise, the hole 22 is large enough to give free passage for the arm 15. The form of the arm 15 in this case is an arc of a circle whose center is at the pivot 13.

When the arm of Fig. 5 is raised, the magnetized end 16 lifts several styli, all of which adhere by reason of contact with the magnetized surface. But when they come to the extension 21, all but one are swept off because the hole 22 is only large enough to 85 permit one to pass. The extension 21 therefore acts as a stripper and must, of course, be of some non-magnetic material such as brass.

I have shown the arm 14 as of L-shape. 90 It may in fact be of any shape, and be supported in any way. The essential characteristics of the device are a magnet provided with means such that, when the magnet is inserted into a mass of magnetic bodies and 95 lifted, one of said bodies will be separated from the mass and elevated to a position at which it may be readily grasped. In other words, the device is designed to pick up styli one at a time from a mass of styli 100 contained in a receptacle. The styli in the receptacle are not in any prearranged order, but are in any form in which they may happen to fall.

What I claim is:

1. In a device for separating one body 105 from a mass of others, a magnet, a support for the magnet upon which support the

magnet is movable to thrust it into and withdraw it from the mass, and means by which upon withdrawing the magnet from the mass one body only of those contacted by the magnet will remain magnetically attached thereto.

5 2. In a device for separating one body

from a mass of others, a magnet having one end partly but not completely covered by some non-magnetic material, and a support 10 for said magnet upon which support the magnet is movable to thrust it into and withdraw it from the mass.

BENJAMIN F. HUTCHES, JR.
